P. T. Dodge

UNITED STATES PATENT OFFICE.

EDWARD P. LYNCH, OF DAVENPORT, IOWA.

CULTIVATOR.

SPECIFICATION forming part of Letters Patent No. 378,141, dated February 21, 1888.

Application filed February 26, 1887. Renewed November 21, 1887. Serial No. 255,766. (No model.)

To all whom it may concern:

Be it known that I, EDWARD P. LYNCH, of Davenport, in the county of Scott and State of Iowa, have invented certain Improvements in 5 Cultivators, of which the following is a specification.

This invention has reference to what are generally known in the art as "parallel-motion cultivators," in which the shovel-carrying standards are connected to the laterally-swinging beams or drag-bars through the medium of vertical pivots, and combined with controlling devices by which they are caused to face constantly in the same direction as they are moved laterally with the beam, as represented, for example, in Letters Patent of the United States No. 329,921, granted to me on the 10th day of November, 1885.

The aim of the present invention is to retain the so-called "parallel movement" of the shovels—that is to say, the constant angle of their faces with reference to the line of progression, as in the existing machines—and at the same time to provide for a convenient 25 change in the width or space between the two shovels carried by one beam.

To this end it consists, essentially, in the combination, with the beam and the pivoted yoke or arm through which the standards are 30 connected, of an adjustable connection by which the angle of said arm to the beam may be varied at will, and in other minor features hereinafter explained.

As the machine may be of ordinary construction in all other respects, I have deemed it sufficient to illustrate in the drawings one of the beams or drag-bars and the attendant parts to which my invention is confined.

In the accompanying drawings, Figure 1 is 40 a top plan view of a drag-bar and its adjuncts having my improvement incorporated therein. Figs. 2 and 3 are similar views showing the same in modified form. Fig. 4 is a longitudinal section on the line $x-x$ of Fig. 3. Fig. 5 is 45 an end elevation of the parts shown in Figs. 3 and 4, the shovel-standard being removed.

In the accompanying drawings, A represents a drag-bar or beam connected at its forward end by a vertical pivot, B, to a sleeve, C, arranged to revolve around the horizontal axle D, or other suitable support, attached to or

forming a part of the frame of the cultivator, in the ordinary manner. These details may be modified at will, the only requirement being that the rear end of the beam shall be free 55 to swing vertically and laterally in the usual manner.

E represents a horizontal yoke or arm extending through or across the drag-bar near its rear end. This yoke, to the ends of which 60 the shovel-carrying standards G are pivoted, is connected by a rod, H, lying parallel with the drag-bar, to the sleeve C.

In their general construction and arrangement the above parts are similar to those in 65 general use, the rod H, which swings laterally with the beam and remains at all times parallel therewith, serving to hold the yoke E and the faces of the shovels at a constant angle to the line of progression as they are moved laterally with the beam.

In machines as heretofore constructed there was no provision for changing the distance between the two shovels, as is frequently demanded in the use of the machine. To this 70 end I provide for changing at will the angle of the arm or yoke E to the line of travel, the effect of such change being to vary the distance between the paths followed by the two shovels.

In Fig. 1 I have shown a simple mode of thus adjusting the rod H, consisting in dividing the same transversely and providing the adjacent ends with right and left hand threads and connecting them by a long nut, I, the rotation 85 of which will serve to lengthen or shorten the rod. As the rod is shortened, the angle of the arm E to the line of travel will be increased and the distance between the paths of the shovels diminished, and, on the contrary, as 90 the rod is lengthened, the yoke E will be brought to a position more nearly at right angles with the line of travel and the distance between the paths of the two shovels increased.

In order that the faces of the shovels may be 95 placed at the proper angle to the line of travel under different adjustments to the yoke E, I make the upper ends of the standards of a round form, seat them in grooves in the ends of the yoke E, and secure them by hook-bolts 100 K, or equivalent fastening, as shown in Fig. 1. This construction permits the standards to

be turned about their vertical axes and secured in different positions. If preferred, however, the standards may be fixed rigidly to the ends of the yoke and the shovels made adjustable around their lower ends in either of the various modes now practiced in the art.

In Fig. 2 I have represented my invention embodied in another form. In this example the shovel-standards, instead of being attached to opposite ends of a single yoke or arm, are attached to two arms, E, connected to the beam by vertical pivots and extending in opposite directions therefrom at different points in its length. In this case the controlling-rod H, jointed at the forward end and lying parallel with the beam, as before, is connected to both arms, the effect being, as in the first example, to maintain a constant direction of the shovels as they move laterally with the beam. The variation in the length of the controlling-rod will have the same effect in this form of the machine as in that first described. In this form of the device I show the divided connecting-rod, its two ends provided with a series of holes and connected by bolts a, so that it may be varied in length by changing the position of the bolts.

In Fig. 3 I have represented a construction similar to that in Fig. 1, except that the controlling-rod is made continuous and its rear end provided with a series of holes, through either of which a vertical pivot connecting the rod with the yoke E may be inserted, thus changing the angle of the yoke in relation to the beam, the effect being precisely the same as in the preceding examples.

Figs. 3, 4, and 5 illustrate another mode of attaching the standards to the end of the yoke, in order that they may be turned horizontally to compensate for changes in its horizontal position. In this form the ends of the yoke are rounded to receive blocks K, in the outer

faces of which the standards are seated. The rounded end of the yoke is slotted horizontally, and a bolt, L, passes outward there-through, through the block a, and through or past the standard into a bearing-block on its outer side, where a nut, M, is applied. The bolt serves to bind the parts firmly together. When loosened, it admits of the block being turned horizontally around the end of the yoke, in order to move the standard and bring the face of its shovel in the required position to the line of progression.

I am aware that a beam composed of two parallel members, each carrying a shovel, has been provided with a plate connecting said members at the rear end, said plate made adjustable in length to vary the distance between the rear ends of the two members and between the shovels carried by them, and this I do not claim.

Having thus described my invention, what I claim is—

1. The laterally-swinging beam or drag-bar, a cross head or arm connected thereto by a vertical axis, two shovel-standards carried by said cross-head, and a longitudinally-adjustable connecting-rod, H, whereby the horizontal angle of the cross-head to the line of draft may be varied.

2. The laterally-swinging beam, the arm or arms pivoted thereto, the adjustable rod H, controlling the position of said arm, the shovel-standards, and the standard-fastening devices adapted to permit the standards to be turned horizontally in relation to their support.

In testimony whereof I hereunto set my hand, this 10th day of January, 1887, in the presence of two attesting witnesses.

EDWARD P. LYNCH.
